DESIGN FOR A BABY'S BOOTEE

Florence L. Bécard, Irvington, N. Y.

Application October 30, 1944, Serial No. 116,045

Term of patent 14 years

(Cl. D7—7)

To all whom it may concern:

Be it known that I, Florence L. Bécard, a citizen of the United States, residing at Irvington, in the county of Westchester and State of New York, have invented a new, original, and ornamental Design for a Baby's Bootee, of which the following is a specification, reference being had to the accompanying drawing, forming a part thereof.

I claim:

The ornamental design for a baby's bootee, as shown.

FLORENCE L. BÉCARD.
